UNITED STATES PATENT OFFICE.

ARTHUR BRUCE SPERRY, OF NEW YORK, N. Y., ASSIGNOR, BY MESNE ASSIGNMENTS, TO
WESTERN ELECTRIC COMPANY, INCORPORATED, A CORPORATION OF NEW YORK.

MACHINE-SWITCHING TELEPHONE-EXCHANGE SYSTEM.

1,246,176.

Specification of Letters Patent.

Patented Nov. 13, 1917.

Application filed July 27, 1915. Serial No. 42,136.

To all whom it may concern:

Be it known that I, ARTHUR BRUCE SPERRY, a citizen of the United States, residing at New York, in the county of New York and State of New York, have invented 5 certain new and useful Improvements in Machine - Switching Telephone - Exchange Systems, of which the following is a full, clear, concise, and exact description.

10 This invention relates to telephone exchange systems employing machine switching, and particularly to that type of system employing automatic finder switches for extending calling lines to connecting circuits, 15 wherein the finders are apportioned to calling lines by an extended starter wire and wherein each group of lines has a finder adapted normally to serve the same, said finder, however, having access to all the 20 lines and being controllable over said extended starter wire to make connection with such lines.

Its object is to provide a circuit arrangement of this character wherein, in case the 25 finder normally assigned to a given group is operating under control of a calling line in another group, a call originating in said first-named group is not held up, but is immediately passed on to the next idle finder.

30 Referring to the drawings, Figure 1 shows all of the apparatus individual to one subscriber's line and a portion of the apparatus individual to another in the same group, and apparatus common to the entire group 35 of lines, that individual to the lines being shown to the left, and that common to the group to the right of the dotted line; Fig. 2 shows a line finder and a first selector with their associated circuits and apparatus; and 40 Fig. 3 is a diagram of the circuit arrangement for passing a call out of a group whose line finder is operating upon another group.

Inasmuch as this general system and the 45 automatic switches employed herein are shown and described in detail in Patent 1,231,013, issued June 26, 1917, to C. L. Goodrum upon which this system is an improvement, only as much of the circuits and apparatus as is essential to an understanding 50 of this improvement will be described herein.

The subscribers' lines 111, 112 terminate in multiple terminals 224, 225 of automatic 55 finder switches, the number depending on the traffic. A multiple test terminal 226 is

associated with each line. Each line is provided with line and cut-off relays v' , u' , and each group of lines with a starting relay c' . This relay is energized upon the initiation of a call in any of the lines to which it belongs, its circuit being completed at the armature and front contact of the line relay v' of such line. The energization of relay c' grounds a terminal 1 (Fig. 2), multiplied to auxiliary or group switches S on the finders in which such group of lines appears, and simultaneously closes the circuit of the primary stepping magnet 205 of the finder serving this group, if such finder be idle. If busy, the arm z' (Fig. 2) of the 60 side switch of this finder will be in position 3, thus extending the starter wire k' to conductor f' which leads to the primary stepping magnet 205 of the next idle finder. Each finder brush shaft (not shown) carries 65 a set of brushes 221, 222, 223 for each group of lines, and may be rotated by the primary stepping magnet 205 thereof to position any set in operative relation to the group of terminals it serves. This set will then, upon 70 the elevation of the brush shaft due to the operation of the secondary stepping magnet 207 of such finder, wipe over such group in search of the calling line. In order to 75 position the proper set of brushes in operative relation to the calling group, the auxiliary switch S' referred to is provided for each finder having a brush z' mounted on the shaft carrying the sets of brushes 221, 222, 223. This brush z' , during the 80 rotary movement of the brush shaft, wipes over group terminals 1, 2, etc., on the auxiliary switch to which it belongs, and when the grounded terminal of the calling group 85 thereon is reached, this rotary movement is stopped, the desired set of brushes at this 90 time being properly positioned below the terminals of the calling line group. The secondary magnet 207 is then operated to 95 elevate the brush shaft.

Assuming the finder of Fig. 2, which is 100 adapted normally to serve group G' (Fig. 3), to be idle, the arm z' (Fig. 2) of the group switch S' of such finder rests on a home contact x' of such auxiliary switch. It is necessary to rotate the brush shaft one 105 step to properly position the set of brushes serving line group G' to wipe over the multiples 224, 225, 226 thereof in search of the calling line therein, upon the subsequent op- 110

eration of the secondary stepping magnet 207. This magnet 207 elevates the brushes and the arrival of the test brush 223 upon the calling line test terminal 226 energizes 5 the cutoff relay u' thereof. This relay in operating, opens the circuit of the group relay c' , which in turn opens the stepping circuit of magnet 207 to stop the finder on the calling line terminals. The calling line is 10 now extended to a first selector and the stepping relay 234 thereof may be operated by the sender s to set such selector in the well-known manner.

The invention will be more readily understood by tracing a call. When the subscriber at substation A (Fig. 1) removes his receiver, a circuit is closed for line relay v' , this circuit leading over the line conductors 111, 112 and through the telephone set at 15 substation A. This relay thereupon closes a circuit for relay c' to start a finder, this circuit leading from the free pole of battery, through the left winding of relay v' , left armature and back contact of cut-off relay 20 5 u' conductor 121, contacts 117, 118 of the line relay v' , conductor d' , relay c' to ground. Relay c' at its right armature and upper front contact thereupon closes a circuit for the primary magnet 205 (Fig. 2), to rotate 25 the brush shaft to position the set of brushes on the brush rod individual to a calling group in operative relation to the terminals of such group, assuming that the line finder normally associated with the starter wire k' 30 be idle. Under such assumption the arm z' of the finder brush rod is in contact with home segment x' . This circuit is as follows: free pole of battery (Fig. 2), magnet 205, conductors 212, 275, arm 210, conductors 209, 208, 35 conductor 266, armature and back contact of magnet 205, conductor 204, armature and back contact of magnet 203, conductors 202, p' , arm i' , conductor k' , slow relay b' , conductor h' , right armature and upper front 40 contact of relay c' to ground. The magnet 205 rotates the shaft one step and carries arm z' of group switch S' into contact with group segment 1, grounded by the energization of relay c' , when a circuit is closed for magnet 50 217 which is the side switch escapement magnet, and magnet 205 in series as follows: free pole of battery, magnet 205, conductor 212, magnet 217, conductor 218, arm 216 and its first contact, conductor w' , arm z' , contact 55 1 of switch S' , conductor q' , armature and front contacts of relay c' to ground. The circuit for stepping magnet 205 previously traced is at this time open at the armature and back contact of said magnet and therefore, is not in shunt of the circuit just 60 traced for magnet 217. The escapement magnet 217 energizes and the magnet 205 remains energized. Magnet 217 in attracting its armature allows the side switch to 65 move to position 2, in which position the

circuit for the magnets 217, 205 is maintained, this circuit being as follows: (Fig. 2) free pole of battery, magnet 205, conductor 212, magnet 217, conductor 218, arm 216 now in position 2, conductor 287, conductors 202, p' , arm i' , conductor k' , relay b' , conductor h' , right armature and upper front contact of relay c' to ground. In parallel with the circuit just traced, the following circuit is closed for the secondary stepping magnet 207: free pole of battery, magnet 207, conductor 219, arm 210 and its second contact, conductors 209, 208, armature and back contact of magnet 207, conductor 266, right armature and front contact of escapement magnet 217, conductor 267, conductor 204, right armature and back contact of release magnet 203, conductor 202, conductor p' , arm i' and its second contact, conductor k' , relay b' , conductor h' , right armature and upper front contact of relay c' to ground. The magnet 207 by interrupting its own circuit 75 70 75 80 85 90 95 100 105 110 115 120 125 130 135 140 145 150 155 160 165 170 175 180 185 190 195 200 205 210 215 220 225 230 235 240 245 250 255 260 out of a group while the line finder normally assigned thereto is operating. Ordinarily a calling subscriber of a group would be blocked as long as the finder adapted normally to serve such group is operating, and could not start an idle finder until its associated finder had fully operated and had extended the starter wire to the next finder, since the starting conductor k' includes the 5 side switch arm i' , which advances during the operation of the finder in connecting with a calling line, and such starting wire k' is not extended to the next idle finder until the side switch arm i' reaches its third 10 contact. The circuit arrangement about to be described operates to extend the starting ground to the next idle finder immediately, if the associated finder is operating to connect with a calling line in another group. 15 This will be more readily apparent from a consideration of Figs. 1, 2 and 3.

Assuming that a subscriber in the second group G^2 (Fig. 3) initiates a call, and that the finder normally assigned thereto be in 20 use. The side-switch arm i^2 of such finder would in such case be in engagement with its third contact (Fig. 3). Therefore the energization of the relay c^2 upon the initiation of a call, closes the following circuit 25 to start the next idle line finder, which we will assume to be the finder normally assigned to group G' : ground, armature and upper front contact of relay c^2 , conductor h^2 , relay b^2 , conductor h^2 , arm i^2 and its 30 third contact, starting conductor f^2 , left armature and back contact of relay b' of line group G' , conductor g' , relay a' , to free pole of battery. Relay b^2 by opening its 35 back contact opens the connection between the release conductors n^2 , o^2 to prevent the finder normally assigned to group G^2 from releasing when the parties to the connection involving such finder restore their receivers. 40 Such finder in restoring would restore the side switch arm i^2 and would thus break the starting circuit just traced. Relay a' at its right armature and lower front contact locks itself to starting conductor f^2 , and at its upper front contact connects the 45 grounded conductor f^2 to conductor h' which leads to the primary stepping magnet 50 205 of the finder of group G' (Fig. 2). This circuit may be continued by reference to Figs. 1 and 2. Continuing therefore from 55 conductor h' (Fig. 1), relay b' , conductor k' , side switch arm i' and its front contact, conductors p' , 202, right armature and back contact of release magnet 203, conductor 204, right armature and back contact of primary 60 magnet 205, conductor 266, left armature and back contact of magnet 207, conductors 208, 209, arm 210 and its first contact, conductors 275, 212, primary stepping magnet 205, to battery. The magnet 205 makes and 65 breaks its own circuit, rotating the brush

rod until the arm z' engages the multiple contact 2 of group switch S' individual to calling line group G^2 thereon. A ground is placed on this contact at the right armature and front contacts of relay c^2 by way of conductor g^2 (Fig. 3). When the arm z' engages this segment, a circuit for the escapement magnet 217 and primary magnet 205 is closed, this circuit being independent of the armature and back contact of said primary magnet, whereby the same is maintained energized as before and the motion of the shaft stopped. This circuit may be traced as follows: free pole of battery (Fig. 2), magnet 205, conductor 212, escapement magnet 217, conductor 218, arm 216, conductor w' , arm a' , segment 2 of switch S' , conductor g^2 (Fig. 3), right armature and contacts of relay c^2 to ground. The escapement magnet 217 is energized by 70 the closure of this circuit, and in attracting its armature allows the side switch to move into position 2, in which position this circuit is maintained over the following path: free pole of battery, magnet 205, conductor 212, magnet 217, conductor 218, arm 216, conductors 287, 202, p' (Fig. 3), arm i' and its second contact, conductor k' , relay b' , conductor h' , armature and upper front contact of relay a' , conductor f^2 , arm i^2 and 75 its third contact, conductor h^2 , relay b^2 , conductor h^2 , armature and upper front contact of relay c^2 , to ground. In position 2, the following circuit is closed for the secondary stepping magnet 207, in parallel 80 with the circuit just traced, to move the brushes 221, 222, 223 so positioned over the terminals of the calling line group G^2 : free pole of battery, magnet 207 (Fig. 2), conductor 219, arm 210 and second contact, conductors 209, 208, armature and back contact of magnet 207, conductor 266, right armature and front contact of magnet 217, conductors 267, 204, right armature and back contact of magnet 203, conductors 202, p' , 85 arm i' and its second contact (Fig. 3), conductor k' , relay b' , conductor h' , right armature and upper front contact of relay a' , conductor f^2 , arm i^2 and its third contact, conductor h^2 , relay b^2 , conductor h^2 , right 90 armature and upper front contact of relay c^2 to ground. The magnet 207 at its armature and back contact interrupts its circuit, thus stepping the said brushes 221, 222, 223 95 over the terminals of the calling line group. The cut-off relay u^2 of the calling line corresponding to relay u' of Fig. 1 is operated 100 when the brush 223 reaches the test terminal 226 of such line. This relay at its left armature and back contact deenergizes the 105 group relay c^2 which, by retracting its right armature, opens the circuit just traced for the stepping magnet 207, whereupon finder brushes 221, 222, 223 come to rest upon the 110 calling line terminals. The escapement 115 magnet 217 is deenergized by the retraction of its armature, and the circuit for the stepping magnet 207 is closed again, whereupon the 120 brushes 221, 222, 223 are again stepped over the terminals of the calling line group. The 125 circuit for the escapement magnet 217 is again closed, and the cycle is repeated. The circuit for the stepping magnet 207 is closed again, whereupon the brushes 221, 222, 223 come to rest upon the calling line terminals. The escapement 130 magnet 217 is deenergized by the retraction of its armature, and the circuit for the stepping magnet 207 is closed again, whereupon the brushes 221, 222, 223 are again stepped over the terminals of the calling line group. The circuit for the escapement magnet 217 is again closed, and the cycle is repeated.

magnet 217 is deenergized by the deenergization of the relay c^2 and allows the side switch to move to position 3, whereupon the calling line is extended through to stepping relay 234 of the first selector as before.

Assuming now that while these operations are taking place a subscriber in group G' initiates a call, that is to say, that this call is initiated before the side switch arm 10 i' of the finder normally serving group G' has reached position 3. The energization of the relay a' by the incoming call from group G^2 , just traced, connected conductors r' and s' together at the left armature and 15 front contact of said relay. The initiation of the call in group G' energizes the relay c' as already described. This relay at its left armature closes the following circuit for a relay at the next idle line finder corresponding to a' of group G' . Only three line groups are shown for simplicity, the first, second and tenth. Assume the finder of the tenth group G^{10} to be idle. The circuit for its relay a^{10} may then be traced as 20 follows: ground, left armature of relay c' , conductors s', r', f' , left armature and back contact of relay b^{10} , conductor g^{10} , relay a^{10} , to free pole of battery. Relay a^{10} by its right armature and lower front contact, locks 25 itself directly to grounded conductor f' , and at its upper contact extends said conductor f' to conductor h^{10} , relay b^{10} , conductor h^{10} , arm i^{10} and its first contact, conductor p^{10} , to the primary magnet of the finder normally 30 serving group G^{10} . This circuit may be continued by referring to Fig. 2, and assuming the finder shown thereon to be that normally assigned to group G^{10} , conductors $p', 202$, armature and back contact of release magnet 203, conductor 204, armature and back contact of primary magnet 205, conductor 206, armature and back contact of secondary stepping magnet 207, conductors 208, 209, arm 210, conductors 275, 212, 35 primary magnet 205, to free pole of battery.

Magnet 205 makes and breaks its own circuit thus stepping around the arm i^{10} of the finder normally serving line group G^{10} . When the arm i^{10} reaches multiple 40 contact 1 upon which ground was placed by the attraction of the right-hand armature of relay c' (Fig. 3), the following circuit is closed: free pole of battery, magnet 205 of the finder of group G^{10} , conductor 212, escapement magnet 217, conductor 218, arm 216, conductor w^{10} , arm z^{10} , contact 1 of auxiliary switch S^{10} , conductor g^1 , to ground at the armature and front contacts of relay c' (Fig. 3). It will be noted that this circuit 45 does not lead through the armature and back contact of primary magnet 205, and therefore this magnet is maintained energized in series with the escapement magnet 217. As before, the escapement magnet in 50 energizing moves the side switch into posi-

tion 2, in which position it is maintained energized over the following circuit, still assuming the finder shown in Fig. 2 to be the finder normally serving line group G^{10} : free pole of battery, magnet 205, conductor 212, 55 escapement magnet 217, conductor 218, arm 216, conductors 287, 202, p' , arm i^{10} and its second contact (Fig. 3), conductor h^{10} , relay b^{10} , conductor h^{10} , right armature and upper front contact of relay a^{10} , conductors 60 f', r' , left armature and front contact of relay a' , conductor s' , to ground at the left armature and front contact of relay c' . In parallel with this circuit the following circuit is closed for the secondary stepping 65 magnet 207 of the line finder in question: free pole of battery, magnet 207 (Fig. 2), conductor 219, arm 210 and its second contact, conductors 209, 208, conductor 266, right armature and front contact of magnet 70 217, conductors 267, 204, right armature and back contact of release magnet 203, conductor 202, conductor p' , side-switch arm i^{10} (Fig. 3) and its second contact, conductor h^{10} , relay b^{10} , conductor h^{10} , right armature and upper front contact of relay a^{10} , 75 conductors f', r' , left armature and front contact of relay a' , conductor s' , left armature and front contact of relay c' , to ground. The magnet 207 makes and breaks its own 80 circuit thus stepping the selected set of brushes over the multiples of the calling group G^1 in the line finder of group G^{10} . When the test brush 223 of such finder reaches the test terminal 226 of the calling 85 line, the relay u' is operated over the following circuit: (Fig. 1) free pole of battery, relay u' , conductor 114, terminal 226, brush 223 of the finder, conductor 113, contacts 228, 270, conductor 271, resistance 272, conductor p' , arm i^{10} (Fig. 3), conductor h^{10} , relay b^{10} , conductor h^{10} , armature and upper front contact of relay a^{10} , conductor f' , conductor r' , left armature and front contact of relay a' , conductor s' , left armature 90 and front contact of relay c' , to ground. The relay u' at its left armature and back contact opens the circuit of relay c' which, in retracting its left armature, removes ground from conductor f' thus stopping the 95 finder upon the calling line terminal. The escapement magnet 217 of the line finder is also deenergized by the removal of this ground, and in deenergizing allows the side switch of such finder to advance to its third 100 position, in which the calling line is extended through to the first selector and the relay 234 thereat is energized.

The removal of ground from starting conductor f' by the deenergization of relay c' deenergizes relays a^{10} and b^{10} . The relay b^{10} in closing its right back contact closes the break in the circuit of release conductors o^{10}, n^{10} . When the parties hang up their 105 receivers the release magnet of the connector 110

is energized in the well-known manner and a ground is placed on conductor 277 leading therefrom. The placing of this ground upon conductor 277 closes the circuit of release 5 magnet 203 of the finder as follows: free pole of battery, magnet 203, conductor 279, off-normal contact 280, conductor o' , right armature and back contact of relay b' , conductors n' , 281, arm 284 of the selector side 10 switch and its third contact, conductor 282, brush 283, terminal 284, to grounded conductor 277. When the finder completely restores, the release magnet is deenergized by the opening of off-normal contact 280. 15 The release magnet 203 in attracting its armature restores the side switch in the well-known manner. The release magnet 278 of the selector is energized in parallel with release magnet 203 of the finder and in attracting 20 its armature also restores the selector side switch.

What is claimed is:

1. In a machine switching telephone system, in combination with groups of subscribers' lines, automatic finder switches to which said lines are multiplied, each of said switches being normally allotted to a group of lines, an extended starter circuit, and means operated over said starter circuit 25 when a line calls in one of said groups while the finder switch normally allotted thereto is operating to find the calling line in a second group for starting a second finder switch from its normal position to find the 30 first calling line.
  2. In a machine switching telephone exchange system, in combination with subscribers' lines, finders to which said lines are multiplied in groups, each group of lines 35 having a finder normally adapted to serve the same, driving circuits for said finders, side switches adapted to control said finders, a relay (c') for each group of lines controlled by any line therein to close the driving 40 circuit of the associated finder, said cir- 45
- cuit including an arm of said side switch and its first contact, an extended starter wire adapted to be associated with a group relay (c') by the closure of said side-switch arm with its last contact when the associated 50 finder is taken for use, of a path at each finder in shunt of the side-switch arm thereof, and a relay (a') for each group adapted to be operated by a group relay (c') of another calling group over said extended 55 starter wire and controlling one break in said path, the corresponding group relay (c') controlling another break therein.
3. In a machine switching telephone exchange system, the combination with subscribers' lines, finders to which said lines are multiplied in groups, each group of lines having a finder normally adapted to serve the same, driving circuits for said finders, an extended starter wire for associating idle 60 finders with calling lines, a relay (c') for each group of lines controlled by any line therein to close the driving circuit of the associated finders, a contact arm included in each of said driving circuits having 65 normal and off-normal contacts, and means for transferring said arm to an off-normal contact to associate the group relay thereof by said extended starter wire with the next idle finder when the associated finder has 70 connected with a calling line of its group, of a branch from said extended starter wire to each group relay independent of the corresponding contact arm, and a relay (a') for each group adapted to close one break in 75 the corresponding branch circuit and adapted to be operated over the extended starter wire upon the seizure of its associated finder by a call from another group, the corresponding group relay c' controlling another break 80 85 therein.

In witness whereof, I hereunto subscribe my name this 23rd day of July A. D., 1915.

ARTHUR BRUCE SPERRY.
